R. H. QUACKENBUSH.
DIRECTION SIGNAL FOR AUTOMOBILES.
APPLICATION FILED MAY 6, 1920.

1,438,552.

Patented Dec. 12, 1922.

UNITED STATES PATENT OFFICE.

RALPH H. QUACKENBUSH, OF BALDWINSVILLE, NEW YORK.

DIRECTION SIGNAL FOR AUTOMOBILES.

Application filed May 6, 1920. Serial No. 379,317.

To all whom it may concern:

Be it known that I, RALPH H. QUACKENBUSH, of Baldwinsville, in the county of Onondaga, in the State of New York, have 5 invented new and useful Improvements in Directional Signals for Automobiles, of which the following, taken in connection with the accompanying drawings, is a full, clear, and exact description.

10 This invention relates to certain improvements in directional signals for motor vehicles and is adapted to be mounted upon the upper side of the highest point of the left hand fender in a manner similar to 15 that shown in my pending application, Serial No. 272,141, filed Jan. 20, 1919, so that its semaphore arms may be swung outwardly from a substantially vertical position over the fender to a substantially horizontal position projecting some distance beyond the outer edge of the fender where it may be readily visible by traffic officers, 20 pedestrians and drivers of other vehicles from the front and from the rear of the machine 25 upon which it is mounted to indicate the direction of movement or stoppage of said machine.

The main object is to provide the semaphore arms with wheel segments having 30 grooved peripheries concentric with their axis of movement for receiving suitable operating cables or cords which are connected to solenoid plungers movable tangentially to the peripheries of their respective segments and attached to their corresponding 35 cables, whereby when either solenoid is energized, the corresponding semaphore will be swung from its normal to its operative position.

40 I am aware that the use of semaphore arms hinged to swing from a vertical to a horizontal position has heretofore been practised, but in actual use it is found that the vibration of the machine either by the 45 engine or in passing over uneven road surfaces causes more or less vibration or rattle of the semaphore arms relatively to their housings or other supports resulting in objectionable noise and undue wear of the 50 parts, and one of the specific objects of my

invention is to provide simple and efficient means for automatically engaging and locking each semaphore arm in its normal position of rest against objectionable vibration without materially interfering with the 55 free opening movement of the semaphore.

Other objects and uses relating to specific parts of the device will be brought out in the following description:

In the drawings:

Figure 1 is an end elevation of a directional signal embodying the various features of my invention in which one of the semaphore arms is adjusted to indicate the direction (in this instance to the left) of 60 movement of the vehicle, a portion of the fender upon which the device is mounted being shown in cross-section.

Figure 2 is a side elevation of the same device, the housing and one of the lamp cases being shown in section and the electric circuits being shown diagrammatically.

Figures 3 and 4 are enlarged sectional views taken in the planes of lines 3-3 and 4-4, Figure 1, except that the semaphores 75 are all in their closed positions.

Figure 5 is an enlarged longitudinal sectional view of one of the semaphore arms showing the manner of securing its sections together.

Figure 6 is a side elevation of the means for locking and releasing each of the semaphore arms in and from its closed position.

Figure 7 is a sectional view taken in the plane of line 7-7, Figure 6, except that the 85 movable parts are in their normal positions.

This device is adapted to be mounted upon the upper face of the highest point of the front left hand fender, as —A—, and comprises a base section —1— and a suitable housing —2— which is mounted upon the base —1—, the latter being secured to the fender by means of bolts —3—.

The housing —2— comprises a bottom plate —4— and a sheet metal casing —5—, the bottom —4— being secured by screws —6— directly to the upper face of the base —1— so as to stand in a substantially upright position wholly within the opposite longitudinal edges of the fender —A—.

100

The bottom section —1— is rabbetted at —7— around its entire marginal edge for receiving the lower end of the casing —5— which is secured thereto by screws —8— so that the case may be removed by upward displacement when the screws —8— are withdrawn. The base —1— of the bottom plate —4— is disposed in a substantially horizontal plane, the central portion of the lower side of the base being recessed at —a— to enable its four corners to rest firmly against the upper face of different forms of fender, whether flat or crown shape.

15 The base —1—, plate —4— and case —5— are preferably rectangular in top plan, although the opposite side walls of the case —5— preferably taper upwardly and terminate in a substantially semi-cylindrical upper end —9—, said case being preferably made of a single piece of sheet metal bent at right angles at the four corners and having its edges overlapping at —10— and secured to each other by rivets or equivalent 20 fastening means, thereby producing a substantially water-tight housing for the various parts enclosed therein.

A pair of upright standards —11— are mounted upon and are preferably cast integral with the base plate —4— at the front and rear ends thereof so as to project upwardly in substantially parallel planes in forwardly and rearwardly spaced relation to points near the upper end of the case 35 —5— where they are provided with apertures for receiving a pivotal pin or shaft —12—.

This shaft extends forwardly and rearwardly in a substantially horizontal plane 40 nearer to the outer face of the casing —5— than to the inner face thereof for receiving and supporting a plurality of, in this instance three semaphore arms —13—, —14— and —15— which normally extend downwardly to points in proximity to but a short distance above the upper face of the bottom plate —4— and are adapted to swing in parallel vertical planes about the axis of the pivotal bolt —12— through vertical slots 45 —16— in the outer upright wall of the case —5—.

Said arms being suspended from the shaft —12— in such manner that their centers of gravity are always at the outer side of the 55 vertical plane of their axis of movement, which causes them to close automatically by their own weight and to normally lie mainly within the case, except as their outer edges are provided with flanges —17— of greater 60 width than the slots —16— to form stops for engaging the outer face of the case to limit their inward swinging movement, all of the arms being adapted to swing from their 65 normal vertical positions to horizontal positions substantially coincident with the hori-

zontal plane of their axes of movement as shown in Figure 1.

Each semaphore arm preferably comprises a wheel segment —18— and a blade —19—, the periphery of the segment —18— being concentric with the axis of the pivotal pin or shaft —12— and extends through an arc of 90 degrees or more and is provided with a groove —20— to receive and guide an operating cable —21—, which is attached to 75 said periphery at a point in a vertical plane directly over said axis, while the remaining portion extends loosely around and within said groove and tangential to said periphery so that the power required to move the arm 80 from its normal position to its elevated position will be substantially uniform and will permit the cable —21— to be attached directly to a movable plunger —22— of a solenoid —23— as the means for operating the 85 semaphore.

As illustrated, the coil of the solenoid is secured by means of its tubular core —24— directly to the bottom plate —4— of the casing and extends upwardly from said bottom at the rear of the semaphore arms —19— wholly within the case —5—, the tubular core —24— being extended some distance above the coil —23— to form a 90 guide —25— for the movable plunger —22—.

The vertical axes of the several solenoids including the plungers —22— are tangential to their respective wheel segments —18— to align their cables —21— with the grooves 100 —20— so that when each solenoid is energized in a manner hereinafter described, its plunger will be drawn downwardly to operate the corresponding semaphore arm through the medium of the cable —21—.

In signals of this character, it is only necessary to throw the semaphore arms to their signalling positions for a brief period of time during which the circuit through the solenoid is kept closed through the medium 110 of a suitable switch presently described, and upon the de-energizing of the solenoid by closing the switch, the solenoid arm will be returned to its normal position by its own weight.

Suitable means is provided for holding each solenoid arm in its closed position against undue vibration or rattling, and for this purpose the lower edge of each semaphore arm is provided with a tooth or shoulder —26— adapted to be engaged by a pawl —26— which is pivoted at —28— to a stud —29— on the bottom plate —4—, as shown more clearly in Figure 6, to allow the pawl to rock in a vertical plane about 120 the axis of its pivot.

In addition to this rocking movement, the pawl also has a longitudinal movement which is permitted by providing the pawl with a lengthwise slot —30— for receiving 130

the pivotal pin —28—. This pawl is normally drawn inwardly in the direction of closing movement of the semaphore blade by means of a light coil spring —31— until 5 limited by the engagement of the outer end wall of the slot —30— with the pivotal pin —28—, as shown in Figure —1—, in which position the shoulder —26— on the lower end of the blade —19— is interlocked with 10 the shoulder, as —32— on the outer end of the pawl which normally engages the outer end face of the shoulder —26—.

It is now clear that the semaphore blade will be yieldingly held in its closed position 15 against lateral vibration by means of the coil spring —31— which is of just sufficient tension to resist any tendency of the lower end of the blade to swing outwardly during the vibration of the machine when 20 traveling over uneven road surfaces, but on the other hand is readily overcome by the action of the solenoid upon the blade in opening the same.

That is when the solenoid for any one of 25 the semaphore blades is energized, the arms immediately swing outwardly and upwardly and move the pawl —27— a limited distance in the same direction against the action of the spring —31— and in order that the 30 semaphore arm may be released from engagement with the pawl, suitable means is provided for tripping said pawl immediately following the initial movement of the semaphore arm from its normal position, 35 said means, in this instance, consist in providing the heel of the pawl with a cam face —33— adapted to ride against a fixed cam —34— on the plate —4— as shown in Figure —6—, said cams being arranged in such 40 manner as to rock the heel of the pawl upwardly and to thereby withdraw its stud —32— from engagement with the shoulder —26— immediately following the beginning of the outward movement of the pawl by 45 the semaphore arms, and, as soon as the pawl is tripped from holding engagement with said arm, it is returned to its normal position by the spring —31—, the heel of the pawl being weighted to rock its outer end 50 upwardly as it rides down the incline of the cam —34— aided by the spring —31— which also tends to restore the pawl to a substantially horizontal position.

When the semaphore arm is released and 55 returns by its own weight to its closed position, its shoulder —26— which has an inclined inner end face rides against the shoulder —32—, thereby depressing the corresponding end of the pawl until the shoulder —26— has passed to the inside of the pawl shoulder at which time the latter interlocks with the shoulder —26— to hold 60 the semaphore arm against outward vibration.

65 Mounted in the upper portions of the front

and rear walls of the case —5— are a pair of electric incandescent lamps —35— and —36— which, together with the semaphore arms serve as signals at night, the front light —35— being arranged to give a green 70 light, while the rear lamp is adapted to give a red light, the cases of both of said lamps being provided with openings in the sides thereof to throw the light rays upon the semaphore arms when the latter are adjusted 75 for use.

The solenoids —23— and electric lamps —35— and —36— may be operated by current from a battery —B—, which is controlled by the operator from a switch board 80 —E— having any suitable construction of switches by which either solenoid or the lamps may be energized independently of the others, the return wires for the several electrically operated parts, and also the battery being grounded upon the frame of the machine.

The operation of my invention will now be readily understood upon reference to the foregoing description and the accompanying 90 drawings, and while I have shown the construction preferred, I do not wish to limit myself to the exact details shown and described.

What I claim is:

1. In a directional signal for automobiles, a signaling arm movable from a normal position of rest to a signaling position, means for operating said arm, a detent lever and retracting means therefor for holding the 100 arm in its normal position, said lever having a limited endwise movement in the direction of movement of and by said arm, and a stationary member engaged by said detent lever during said endwise movement for tripping the detent lever from holding engagement 105 with the signalling arm and permitting it to be returned by said spring.

2. In a directional signal for automobiles, a signaling arm movable from 110 a normal position of rest to a signaling position, electrical means for operating said arm, a spring-retracted detent lever for holding the arm in its normal position and having a limited endwise movement in the direction of movement of and by said arm, a cam on said lever, and a stationary member engaged by said cam for tripping the detent as the latter is drawn 115 endwise by the arm against the action of its retracting spring.

3. In a directional signal for automobiles, a vertically disposed housing mounted on one of the mud-guards of the automobile and provided with a vertical slot in one side, a signaling arm pivoted in the housing to swing through said slot and provided with a shoulder on its free end, a detent lever for engaging said shoulder and holding the arm in its normal position of rest against 125

outward swinging movement, said detent lever having a limited endwise movement in the direction of outward swinging movement of and by said arm, a fixed cam for engaging 5 and tripping the detent lever as it is moved endwise and means for retracting said lever endwise after it has been tripped.

In witness whereof I have hereunto set my hand this 20th day of April, 1920:

RALPH H. QUACKENBUSH.

Witnesses:

H. E. CHASE,
Rose G. CARROLL.
